MYER SIGMUN, OF TOLEDO, OHIO, ASSIGNOR OF ONE-HALF TO SUMER SPITZER, OF TOLEDO, OHIO.

RADIATOR.

1,142,536.

Specification of Letters Patent.

Patented June 8, 1915.

Application filed August 17, 1914. Serial No. 857,229.

To all whom it may concern:

Be it known that I, MYER SIGMUN, a citizen of the United States, and a resident of Toledo, in the county of Lucas and State of Ohio, have invented a certain new and useful Radiator; and I do hereby declare the following to be a full, clear, and exact description of the invention, such as will enable others skilled in the art to which it applies to make and use the same, reference being had to the accompanying drawings, and to the characters of reference marked thereon, which form a part of this specification.

15 My invention relates to radiators used for cooling water supplied to water jackets of internal combustion engines.

It has for its object to provide a radiator which may be readily constructed and its parts put together in such a way as to greatly reduce the amount of solder required for closing the seams of the radiator.

It also has for its object to form laterally extending water cells in such a way that the water will be deflected thereby forming laterally moving currents of water in the cells.

It also has for its object to provide section strips which are so made as to cause the air to deflect and thereby produce cross or diagonal currents of air in each section as the air passes through the radiator when it is either blown or drawn through or when the radiator is carried by an automobile through the air.

35 The invention may be contained in many forms of constructions usable for different purposes, all of which come within the purview of my claims hereinafter appended. To show the practicability of my invention, 40 I have selected one of such constructions as an example and shall describe it hereinafter. The construction selected is illustrated in the accompanying drawings.

Figure 1 illustrates a front view of the 45 radiator, part of the honey-combed portion only being shown. Fig. 2 illustrates the manner in which the section strips are cut. Fig. 3 illustrates one of the strips folded. Fig. 4 illustrates two sections mounted side by side. Fig. 5 illustrates a sectional view of the sections shown in Fig. 4 and Fig. 6 illustrates the partition or reinforcing plate located between the sections.

The radiator 1 shown in Fig. 1 is provided with the usual upper and lower compartments 2 and 3 which are connected to the gasolene engine in the manner well known in the art.

4 are sections through which the water passes as it is cooled falling from the compartment 2 to the compartment 3. The sections are formed of vertically disposed strips which are bent so as to form water cells through which the water passes vertically and air cells through which the air passes horizontally or transverse to the direction of movement of the water which cools the water as it descends through the radiator. Each section is composed of a strip 10 which is corrugated forming semi-cylindrical corrugations 11 and plane portions 12. The semi-cylindrical corrugations 11 are slotted, the slots 13 being formed along two lines, one line being located near one edge 14 of the strip and the other line being located centrally and lengthwise of the strip. The plate 10 is then bent along the lines 16 of the edge of the slots. The edge 14 of the strip is bent over the edge 15. The adjacent parallel lines 16 being located a short distance apart gives thickness to the water cells of the radiator when plate 10 is bent to form the water cells. The edge 14 will, when the portions of the plate 10 are bent over the edge 15, close the edges of the plane portions 12 and reinforce the laterally extending edges of the bulging portions located on one side of the section. When the parts have been folded together the plate is pressed so as to push the corrugated parts 11 together bringing the end edges of the corrugated parts in close proximity to each other. The curvature produced in forming the semi-cylindrical corrugations cause these portions to bulge when the edges are thus brought together. The edges of the portions 11 are then pinched together leaving the portions intermediate the ends bulged which give space for water circulation.

By reason of their bulged formation, the water is caused to deflect and circulate through the laterally extending portions of the water cells. The edges of the portions 11 are then soldered to form closed seams, while the edges of the portions 12 lap over the edge 15. The lapped edge

12 and openings 17 formed at the ends of the cells are also soldered to completely close the water cells. Corrugated plates 20 are located between the sections thus formed. 5 The plates 20 may be angularly corrugated or semi-cylindrically corrugated. Each plate 20 is provided with holes 21 which are staggered transverse the plate and extend along the corrugations. As the air passes 10 through the radiator the corrugations of the plate 20 produce diagonal currents of air within the air cells of the radiator, the air being caused to deflect transversely as it passes through the radiator. Also, the openings 15 allow the air to circulate back and forth through the cells located on opposite sides of the plate which causes the air to circulate and be deflected back and forth bringing all parts in the metal into contact with the air, thereby rapidly cooling the water as the air 20 passes through the radiator. This produces an exceedingly efficient radiator.

The construction selected and described, 25 may be greatly varied in the arrangement and manufacture of its parts and in the substitution of elements having equivalent functions and such modifications may be used for many varied purposes and still contain the invention.

30 Having thus described my invention, what

I claim as new and desire to secure by Letters Patent, is,—

1. In a radiator, a strip having spaced corrugations and slotted centrally across the corrugations and near one edge of the strip 35 and folded centrally and having one edge turned over the opposite edge along the slots, forming vertical and transverse water chambers.

2. In a radiator, a strip having spaced 40 corrugations and slotted centrally across the corrugations and near one edge of the strip and folded centrally and having one edge turned over the opposite edge along the slots, forming vertical and transverse water 45 chambers, a corrugated strip located between the first-named strips and spaced by the corrugations of the first-named strip and having openings arranged along the corrugations of the last-named strip and staggered 50 in their arrangement across the corrugations of the last-named strip.

In testimony whereof, I have hereunto signed my name to this specification in the presence of two subscribing witnesses.

MYER SIGMUN.
